[57] CLAIM

The ornamental design for an optical disc drive, as shown and described.

DESCRIPTION

FIG. 1 is a perspective view of an optical disc drive showing our new design in a state where the cover is opened;

FIG. 2 is a front view thereof;

FIG. 3 is a rear view thereof;

FIG. 4 is a top view thereof;

FIG. 5 is a bottom view thereof; and,

FIG. 6 is a left side view thereof, the right side view being a mirror image of the left side.
